United States Patent Office.

LEVERITT H. OLMSTED, OF NEWARK, NEW JERSEY, ASSIGNOR TO
WRIGHT & SMITH, OF THE SAME PLACE.

Letters Patent No. 65,420, dated June 4, 1867.

IMPROVEMENT IN TIGHTENING AND LOOSENING WHEELS ON SHAFTS.

The Schedule referred to in these Letters Patent and making part of the same.

TO ALL WHOM IT MAY CONCERN:

Be it known that I, LEVERITT H. OLMSTED, of the city of Newark, in the county of Essex, and State of New Jersey, have invented an Improvement in Tightening and Loosening a Wheel on a Shaft; and I do hereby declare the following to be a full and exact description thereof, reference being had to the drawings that accompany this specification, and make part of the same.

The nature of my improvement consists in a provision for tightening and loosening a wheel which operates from the centre of the shaft. In the drawings—

Figure 1 represents the various parts in their combination.

Figure 2 shows the screw, the taper-slide, and the blocks or pins.

In the end of a shaft, A, a hole is bored to admit the tapering slide B. At the outer end of the hole a thread is cut in the shaft suited to the screw y, which is on the taper-slide B. Near the extreme end of the taper-slide B a block or blocks or a pin or pins, X, are inserted into the shaft A, the outer ends of the blocks or pins being turned even with the surface of the shaft. The inner end is tapered to fit the taper-slide B. A turn of the screw y forces the pins or blocks X against the inner surface of the eye or hub of the wheel C, tightening or loosening it on the shaft A, as the case may require.

What I claim as new, and desire to secure by Letters Patent, is—

The combination and arrangement of the slide B, screw y, and pin or block X, constructed and operating as described, for the purpose of tightening or loosening wheels on shafts, as set forth.

L. H. OLMSTED.
